6 Claims. (Cl. 66—156)

This invention relates to interchangeable pattern carriers or pattern controlling devices for jacquard cards particularly for knitting machines.

There are jacquard cards existing, for example, for flat knitting machines, which are provided with interchangeable pattern carriers permitting the pattern to be changed. The known interchangeable pattern carriers have, however, various drawbacks in consequence of which they could be introduced into practice only with moderate success. Amongst these drawbacks are unreliability of operation, due to the fact that the pattern carriers become too easily detached from the card, or else the pattern carriers are so firmly secured to the card that they can be removed only by means of special implements, which procedure is detrimental above all to cards provided with a fine division of their apertures and used, for example, in machines having multiple mechanisms. A further drawback of the known pattern carriers resides in the presence of clamping springs the open ends of which are prone to become tangled by hooking to the back-side of the card.

The interchangeable pattern carrier constructed according to the present invention avoids all these drawbacks.

According to the invention, the face plate provided on the pattern carrier has arranged on the underside thereof a clasp which extends from one side of the face plate to an opposed side thereof and is provided at each of its end portions with a kerf, which serves for interengagement with the respective edge of an aperture in the card and at the same time for supporting, that is, detachably securing the pattern carrier to the jacquard card.

By this means the pattern carrier can be put into use in a manner similar to that of the two parts of snap fasteners so that the insertion of the pattern carrier in the jacquard card as well as the removal therefrom is simplified and the carrier is securely held in position thereon.

Advantageously, the spring clasp is fixed to the face plate of the pattern carrier at one of its end portions, while the other end portion bears resiliently on the face plate. By this means, very great resiliency of the curved spring yoke of the clasp is obtained, which yoke in certain circumstances may be of very small dimensions, so that an easy insertion and removal by exerting an adequate pressure on the free end portion of the clasp is permanently ensured.

In the drawing several embodiments of the

invention are illustrated by way of example only, in which:

Fig. 1 is a perspective view of a part of a jacquard card with the pattern carrier inserted in position; 5

Figs. 2, 2a, 2b illustrate a first embodiment in three views seen from different sides, and

Figs. 3, 3a, 3b and 4, 4a, 4b each show in similar views a second and a third embodiment, respectively. 10

The pattern carrier lug for covering an aperture *a* in the jacquard card bordered by edges adjacent the opposing longitudinal marginal portions of said card, as shown in Figs. 1, 2, 2a and 2b, is provided with a face plate *b* on the underside of which a spring clasp *c* is arranged one end portion of which is fixed to the face plate *b*, at *d*, by forming an integral piece of material with this plate. Alternatively, this end portion of the clasp may be connected to the face plate, for example, by soldering. The other or free end portion *e* of the clasp *c* bears resiliently against the backside of the face plate *b*. The clasp *c* thus extending with its curved yoke from one end of the face plate *b* to the opposite end 15 thereof is provided at its end portions with kerfs *f* and *g*, respectively, provided by corresponding bends formed in the clasp. By means of these kerfs *f*, *g* the clasp *c* engages over the respective edges of one of the apertures *a* and 20 interengages with the latter by spring action, whereby the jacquard card enters into firm supporting engagement with the pattern carrier 25 from two directions.

After the pattern carrier has been removed from the card, the relaxed clasp *c* projects with its free end portion *e* somewhat beyond the corresponding end of the face plate *b*, as shown in Fig. 2, so that pressure can readily be exerted on this end portion of the clasp by hand for 30 temporarily deforming the clasp particularly, for removing the pattern carrier from the aperture in the card. The yoke of the clasp *c* is provided with a bossed middle portion merging with flared straight guide planes leading to the kerfs 35 *e* and *f*, respectively, so that the pattern carrier can be inserted with ease merely by exerting pressure from above on the face plate to be guided toward the jacquard card by hand, while the clasp is temporarily deformed. With this 40 construction the face plate *b* and the clasp *c* are both of the same width as the aperture *a* in the card by which means the pattern carrier is given support by the jacquard card also in the lateral 45 directions.

- In contrast thereto, the embodiment shown in Figs. 3, 3a and 3b is provided with a pattern carrier having a larger face plate. This face plate *b* is adapted to cover, for example, about 5 to 10 apertures in the card at the same time. The clasp *c* arranged in the middle of the length of the face plate *b* is of a width corresponding also in this case to that of an individual aperture in the card.
- 10 In distinction therefrom, in the embodiment shown in Figs. 4, 4a and 4b, two clasps *c*, *c*, are arranged on the face plate *b*. These are positioned in the middle portion of the face plate *b* considering the length of the latter and are spaced at a distance of two apertures *a* in the card, whereby the pattern carrier can be securely fastened to the card.

In all the exemplifications explained the longitudinal direction of the clasp is parallel with the transverse direction of the jacquard card. Therefore, for the interchangement of the pattern carrier the clasp needs to be influenced only from a side of the jacquard card and of the pattern carrier, which is altogether freely accessible, so that the connecting tongues separating adjacent apertures in the card are not detrimentally affected and no special implements are needed even with the smallest divisions of the apertures.

What I claim is:

- 30 1. In an interchangeable pattern carrier for jacquard cards particularly for knitting machines, a jacquard card, a pattern carrier for insertion in apertures in said card bordered by edges adjacent opposing marginal portions of said card, a face plate on said carrier for the reception of a pattern, at least one clasp arranged on the underside of said face plate so as to extend from one side of said face plate to an opposed side of said plate, and end portions 35 on said clasp, one of said end portions being fixed to said face plate and the other bearing resiliently against said plate and each of said end portions being provided with a kerf for interengagement with said edges of the respective card aperture, for holding and detachably securing said pattern carrier on said card.
2. In an interchangeable pattern carrier for jacquard cards particularly for knitting machines, a jacquard card, a pattern carrier for insertion in apertures in said card bordered by edges adjacent opposing marginal portions of said card, a face plate on said carrier for the reception of a pattern, at least one stirrup-like clasp arranged on the underside of said face plate so as to extend from one side of said face plate to an opposed side of said plate, a bowed middle portion provided on the yoke of said stirrup-like clasp, flared guide surfaces merging with said bowed middle portion, and end por-

tions on said clasp each provided with a kerf at the junction with the flared end of the respective guide surface, said kerfs interengaging with said edges of the respective card aperture, for holding and detachably securing said pattern carrier on said card, by insertion of said carrier in said card merely by exerting pressure on said face plate.

3. In combination with an apertured jacquard card, particularly for knitting machines, an interchangeable pattern controlling lug for insertion in apertures of said card, comprising a face plate, at least one clasp thereon formed by a resilient member extending over the under face from one edge of said face plate and bearing 10 against the opposite edge thereof, said member being grooved to engage the edges of the respective aperture and to detachably secure said lug on said card.

4. In combination with an apertured jacquard card, particularly for knitting machines, an interchangeable pattern controlling lug for insertion in apertures of said card, comprising a face plate, at least one clasp thereon formed by a resilient member extending over the under face 15 from one edge of said face plate and fixed at one end to one edge of said plate and with its free end bearing against the opposite edge of said face plate, said member having kerfs adapted to engage the edges of the respective card aperture and to 20 detachably secure said lug on said card.

5. In combination with an apertured jacquard card, particularly for knitting machines, an interchangeable pattern controlling lug for insertion in the card apertures, comprising a face 25 plate adapted to cover a plurality of said apertures, at least one resilient clasp fixed with one end to one side and extending over the under face of said plate and bearing with its free end against the opposite side of said face plate, the 30 end portions of said clasp each having a kerf adapted to engage the end edges of the respective card aperture and to detachably secure said lug on said card.

6. In combination with a jacquard card, having oblong apertures, an interchangeable pattern controlling device for covering apertures of said card, comprising a face plate, clasps thereon each formed by a resilient yoke shaped member extending over the under face of said face plate 35 and fixed at one end to one of the edges of said face plate and at its free end bearing against the opposite end edge of said face plate to form with the latter a closed loop, said member being grooved at its ends to engage the narrow edges 40 of an aperture and to detachably secure said device on said card.

HANS KORBER.
